UNITED STATES PATENT OFFICE.

JASON H. GREENSTREET, DECEASED, LATE OF INDIANAPOLIS, INDIANA; BY CHARLES J. GREENSTREET, EXECUTOR, OF CHICAGO, ILLINOIS.

PAPER-BOARD MACHINE.

Application filed September 2, 1924. Serial No. 735,485.

This invention relates to a paper folding machine for forming a paper board provided with a plurality of folds therein, such a board being illustrated and claimed in a 5 co-pending Patent 1,507,372.

This invention is one form of a machine for forming paper board of the character described, another form of said machine being illustrated and claimed in a co-pending Patent 10 1,507,373.

Certain features of the present machine are common to those of the machine before mentioned and are not herein claimed.

The chief object of the invention is to provide 15 a device for folding a paper strip or sheet and securing said folds together to form a paper board of the character indicated.

The chief feature of the invention consists 20 in the simplicity of construction, compactness of arrangement and certainty of operation, whereby a sheet of paper is creased, pasted and secured together in folded relation to form a paper board.

Another feature of the operation is the 25 association and continuous connection of the several parts with each other, whereby said parts operate in predetermined timed relation and in no other relation and, therefore, there is secured certainty of operation.

The full nature of the invention will be understood from the accompanying drawings and the following description and claims.

Fig. 1 is a top plan view of a machine of 30 the character described, parts being broken away and reference being had to the allowed co-pending application, Serial No. 464,665, for a complete disclosure of the entire machine.

Fig. 2 is a side elevational view of the invention, parts being broken away to show other parts in section, the parts illustrated being shown in the creasing and adhesive 45 applying positions.

Fig. 3 is a similar view of the same parts in the folding and adhesive receiving position.

Fig. 4 is a similar view of the same parts,

showing said parts in an intermediate position.

In the drawings 10 indicates a suitable platform or table suitably supported and for a full disclosure of one form of such support, reference may be had to the before- 55 mentioned co-pending machine application. In suitable brackets 11 there is pivotally supported a power shaft 12 which carries a power operable means such as a pulley 13. The shaft 12 carries an eccentric pin 14 and 60 pivotally supported by said pin and operable thereby is an arm 15. A pair of said arms terminates in a paper shoving or advancing plate 16 having the serrated edge 17.

The table 10 is suitably slotted as at 18 65 and is also slotted substantially across the entire width of the table as at 19, but there is provided partitions or connecting portions 20 which support the paper while passing over the enlarged apertures 19. The adhesive is applied to the under side of the paper sheet 21 through said apertures. Creasing also is secured therethrough.

Pivotally supported beneath the table 10 are a pair of arms or levers 22. These are 75 pivoted at 23. Each arm is pivotally connected at 24 to an angular link 25 which is positioned in and extends through the slot 18. The opposite end of the link 25 is provided with an elongated slot which receives 80 a pin 27 carried by the actuating arm 15. The two spaced arms 22 support a casting 28 which is suitably notched or recessed to clear the supporting partitions 20 of the table thereby permitting the other portions 85 29 of said casting to be exposed and project upwardly beyond the level of the support 10 and engage the under side of the paper 21, as shown clearly in Fig. 2.

The edge 29 of said casting 28 is adapted 90 to bear upon a supply roller 30, which is rotated in a trough 31 containing a suitable adhesive material 32 which may be of a character such as silicate.

Pivotally supported at 33 is a lever 34 95 having an extension 35 with which is associated spring 36 for returning said lever into the position shown in Fig. 3. Each lever 34

is provided with an elongated slot 37, in which rides a pin 38 carried by the arm or lever 22. When the arm or lever 22 is tilted upon its pivot 23, said tilting movement causes the pin 38 to ride in the slot 37 of the lever 34 and tilt said lever 34. Two spaced levers 34 carry a creasing plate 39, suitably recessed so as to clear the longitudinal supporting partitions 20 of the table 10.

10 Pivottally supported upon one, or if desired, upon each of the arms 22 and at 40 is a detent 41 which is adapted to engage a ratchet wheel 42 concentric with the roller 30 and to rotate said roller in the tank 31 containing the silicate 32. A spring 43 normally maintains said detent in ratchet engagement. Thus, as shown clearly in Fig. 3, upon the forward throw of the actuating arm 15, link 25 positively tilts the lever 22 to cause the adhesive supporting surface 29 to be supplied with adhesive from roll 30. Simultaneously with said movement detent 41 rotates ratchet 42 which rotates the adhesive supplying roller 30 to deposit adhesive 25 upon the portion 29.

In this forward movement of the foregoing parts the plate 16 carries forward the strip of paper 21 at a greater rate than it has heretofore been moving and at a greater rate than the preceding portion is moving, so that it tucks the following portion of the paper under the preceding portion of the paper to form a fold. This fold, as shown clearly in Fig. 3, includes the adhesive covered portions so that there is no adhesive exposed upon either of the exposed surfaces of said folded sheet when folded. Upon the return movement of the arm 15 and substantially at the end of said movement the surface 29 containing the adhesive engages the paper sheet 21 and applies adhesive thereto see Fig. 2. Upon the initial return movement of the arm 15, the plate 16 causes the paper to be creased by reason of the engagement of the paper covered plate 16 upon the creasing member 39. Continued forward movement tilts the creasing member 39 out of engagement with the paper portion previously creased and this position is shown in 50 Fig. 4.

Continued advancing movement of the actuating arms 15 with folding plate 16 completes the paper fold covering the adhesive applied portions thereof and simultaneously deposits additional adhesive upon the adhesive applying member 29.

Pivottally supported above the table at the portion where the creasing and adhesive applying and folding operations take place is a pivottally supported plate 50 that bears upon the folded paper and tends to maintain the folds in folded relation until such time as the folded paper is engaged by the conveying means and said plate also serves as a per 60 guide to the conveying means. Herein

said conveying means is illustrated as a pair of endless belts 51 and 52, which have their adjacent portions travelling in the same direction and between which is positioned the folded paper.

It is to be understood that while creasing and folding the actuating bar 15 has a greater linear speed than the belts 51 and 52, whereby the creasing and folding is accomplished.

The invention claimed is:

1. In a paper board machine, the combination with paper creasing means, paper folding means, and adhesive applying means, of means for positively actuating the adhesive applying means in timed relation with the paper folding means, and means connecting the adhesive applying means and the paper creasing means for actuating the latter by the former in timed relation therewith and with the paper folding means.

2. A device as defined by claim 1, characterized by the actuating means including a pin and slot continuous connection between the paper folding means and the adhesive applying means, and the connecting means including a pin and slot continuous connection between the adhesive applying means and the paper creasing means for securing predetermined movements therebetween and the means connected through the adhesive applying means.

3. A device as defined by claim 1, characterized by the adhesive applying means including a pivotally mounted adhesive applying plate.

4. A device as defined by claim 1, characterized by the adhesive applying means including a pivotally mounted adhesive applying plate, and further characterized by the connecting means including a pin and slot continuous connection between the adhesive applying means and the paper creasing means.

5. In a paper board machine, including paper folding means and a paste receiving reservoir, the combination of a paste supplying roller positioned adjacent the reservoir for conveying adhesive upon its surface and supplied thereby, a pivotally mounted adhesive applying plate adapted to intermittently engage said roller and remove adhesive therefrom and successively apply the same, means operatively connecting said pivotally mounted intermittently applying adhesive plate and said roller for rotating the roller in timed relation with the tilting of said plate toward the roller for supplying adhesive to said plate, and a continuous connection between said paper folding means and the adhesive applying plate for tilting the latter to intermittently apply adhesive in timed relation with the movement of the paper folding means.

6. In a paper board machine, the combi-

nation with a paper folding plate, a paper creasing plate pivotally supported adjacent and in the path of said paper folding plate, and means normally tending to maintain said paper creasing plate in the creasing position, said creasing plate being movable into non-creasing position in the movement of said paper folding plate, of means continu-

ously and positively connecting the paper folding plate and the paper creasing plate 10 for operating the same in timed relation with each other and one from the other.

In witness whereof, I have hereunto affixed my signature.

CHARLES J. GREENSTREET,
Executor of Jason H. Greenstreet, Deceased.
